WATERPROOF CONTAINER LATCH

Joseph Bafia, Chicago, Ill.

Application April 4, 1940, Serial No. 327,745

1-Claim. (Cl. 292—58)

The invention relates to improvements in waterproof containers and locks therefor, and more particularly to an hermetically sealed container adapted to be carried by bathers, swimmers and others for keeping articles such as cigarettes, cosmetics, matches or money dry.

An object of the invention is to provide a simply constructed, inexpensive, waterproof container embodying a novel locking mechanism for hermetically sealing the receiving opening therein.

Another object is to provide a waterproof container in the form of a purse, with novel means on opposed faces of its complementary jaw portions arranged to co-act to hermetically seal said jaw when the later is closed and locked.

Another object of the invention is to provide an efficient inexpensively constructed easily actuated lock.

The foregoing and such other objects of the invention, as will appear hereinafter as the description proceeds, will be more readily understood from a perusal from the following specification in which reference is had to the accompanying drawing wherein:

Fig. 1 is a side elevational view, partly broken away, of the improved container.

Fig. 2 is a framgentary transverse sectional view taken substantially line 2—2 of Fig. 1.

Fig. 3 is a sectional view similar to Fig. 2 showing the container jaw open.

Fig. 4 is an end view of the lock element taken substantially on line 4—4 of Fig. 3.

Fig. 5 is an end view of the other lock element taken substantially on line 5—5 of Fig. 3.

Fig. 6 is a fragmentary plane view of the container showing the parts illustrated in Fig. 3.

Fig. 7 is a view similar to Fig. 6 but on an enlarged scale showing the locking device closed and locked and partly in section.

As best shown in Fig. 1 the improved container 11 preferably is made of waterproof material, such as for example, rubber, rubberized fabric, oilskin or the like, and preferably as an opening 12 along one edge providing complementary opposed jaw portions adapted to be moved toward and away from each other to effect opening and closing of the container. The complementary jaw portions are each suitably reinforced by a rigid strap 13 which, in the illustration, is substantially arcuate and which have their associated end portions hingedly connected together at 14 as best shown in Figs. 2 and 3. The straps 13 preferably are entirely embedded within the material from which the container is made consequently said

members are adequately protected against corrosion or other damage. When the complementary jaw portions are brought together to close the container, the opposed resilient faces 15 of said portions engage. Non-registering continuous ridges or beads 16, provided one on each face 15, are adapted to be compressed to hermetically seal the opening 12.

Although various types of known latches or locks may be employed with limited success to retain the jaw portions closed for hermetically sealing the container opening 12, it is preferable that the novelly constructed latch or lock best illustrated in detail in Figs. 3 to 7 inclusive, be provided. The lock preferably consists of complementary elements 17 and 18 one of which is fixedly secured to one of the jaw portions by means of a substantially T-shaped plate 19 and the other of which is fixedly attached to the other jaw portions by a similar substantially T-shaped plate 21. The T-shaped plates 19 and 21 may be attached in any suitable manner, however it is preferable that they each be secured to one strap 13 by screws or rivets 22.

25 The lock element 18 preferably includes a substantially cylindrical housing 23 riveted, welded or otherwise attached at one end to the plate 19. Its other or free end is offset, as at 24, to provide diametrically opposed shoulders 25 disposed in a substantially horizontal plane below the plane of the longitudinal axis of the housing 23.

A pin 26 of a diameter substantially less than the inside diameter of the housing 23 is rotatably mounted at one end in the mounted end 35 of the housing 23, as best shown in Fig. 7, on the longitudinal axis of the housing. The free or forward end of the pin 26 preferably extends beyond the free shouldered end of the housing 23 and has integral therewith a finger-piece 27 which extends substantially at right angles thereto for selective engagement with either of the diametrically opposed shoulders 25.

The other complementary lock element 17 also 45 consists of a tubular shell 28 rigidly secured in any suitable manner at one end to the attaching plate 21. The member 28 has a wall thickness substantially less than the width of the annular space between the pin 26 and the inside periphery of the housing 23 so that when the jaw portions are brought together in closed position, the element 28 telescopes freely into the housing 23 and the pin 26 telescopes into the shell 28. Obviously, suitable means must be provided to allow 50 for free uninterrupted passage of the finger

piece 27 when the parts 23 and 28 are telescoped. To this end, the wall of the shell 28 has a longitudinally extending helical slot 29 of sufficient width to accommodate the finger-piece 27.

To close and lock the container the finger-piece 27 is initially arranged in the position substantially as shown in Figs. 4 and 6 in which position it rests upon one of the shoulders 25. As the parts 23 and 28 are moved into their initial telescoped arrangement, the finger-piece engages the exposed inclined face 31 of the helical slot 29 and as the closing movement continues, is urged or directed by said slot upwardly and then over downwardly until it lies substantially against the other shoulder 25.

The complementary jaw portions of the container are, when the lock is in this position, in substantial contact. However, additional pressure is required to bring their opposed beaded faces 15 tightly together to provide the necessary hermetic seal. Accordingly, the inner end of the helical slot 29 terminates in a substantially circumferentially extending slot 32 having at least one of its edges 33 inclined slightly whereby, upon manual movement of the finger-piece 27 along said slot from the position last described upwardly and across the top of the shell 28, the complementary locking elements and likewise the complementary jaws are drawn tightly together.

When the container is closed and locked, movement of the finger-piece 27 from its locked position shown in Fig. 7 is easily affected man-

ually and as soon as said finger-piece is in alignment with the helical slot 29 the normal resiliency of the abutting faces of the jaw portions urges said jaw portions apart thus effecting automatic disengagement from the helical slot.

It should be understood at this time that the waterproof container herein described may readily embody other forms than that shown and that if desired suitable loops 34 or the like may be provided thereon to afford means for attaching the container to a belt or other device for attaching the purse to the body of the user.

I claim:

A latch comprising, in combination, a tubular housing closed at one end, a pin axially arranged in said tubular housing, said pin having a diameter considerably less than the inside diameter of said tubular housing to define an annular space and being rotatably secured against longitudinal movement at one end in the closed end of said housing, a radial finger piece on the free end of said pin, a complementary tubular element arranged to telescope into said annular space, and a longitudinally disposed cam-like slot in the wall of said element terminating at its inner end in a substantially circumferential slot, said cam-like slot opening on the entrance face of said element whereby the radial finger piece enters said slot during telescopic movement of the parts and finally rests in the substantially circumferential slot to detachably secure the parts together.

JOSEPH BAFIA.
